chines Corporation, New York, N. Y., a corpora-
tion of New York

Original application December 2, 1936, Serial No.
113,798, now Patent No. 2,161,564 dated June
6, 1939. Divided and this application November
13, 1937, Serial No. 174,293

3 Claims. (Cl. 178—81)

This invention relates to printing telegraph transmitting mechanisms and more particularly to power operated teleprinters comprising individual power operated units to initiate the control or character signals impressed upon the transmission medium.

An object of the present invention is to provide novel means associated with the power operated units of known construction to control signals initiating members.

The power operated units referred to each comprise a cam supported in a pivoted bell crank member, the said cam adapted to cooperate with a constantly rotating roller. The engagement of the cams with the roller being controlled selectively by character keys. It has been suggested heretofore, when the power operated recording unit is employed in printing telegraph systems, to control the transmitting contact members directly by cams as they are rotated by the cooperating roller. Other suggestions comprise providing extension members protruding at right angles from the bell crank members supporting the cams so that, when the cams are effective to swing the bell crank members, signal transmitting members are operated by the said extension members.

In certain applications it has been found that the suggestions just set forth are unsuitable to control the signal transmission members as desired. The present invention contemplates providing extension members along the major axis of the bell crank members which extend beyond the pivotal axis of the supported cams and engage signal transmitting control members which may be disposed beneath the banks of power operated cam units and power roller. The mentioned signal transmitting control members may be in the form of contacts operated selectively and permutatively by individual permutation members operated by the said extension members of the bell crank members, or the signal transmitting contacts may be controlled and engaged directly by the said extension members.

Another object of the present invention, therefore, is to provide extension means along the major axis of the bell crank member supporting the revolubly mounted cam which are adapted to control the signal transmitting control members directly or indirectly.

Further objects of the instant invention reside in any novel feature of construction or operation or novel combination of parts present in the embodiment of the invention described and shown

in the accompanying drawings whether within or without the scope of the appended claims and irrespective of other specific statements as to the scope of the invention contained herein.

In the drawings:

Fig. 1 is a sectional view of the power operated recording unit.

Fig. 2 is an exploded view of the power operated cam unit. Certain structural details are exaggerated in this view to show clearly the normal position of certain of the operating elements.

Fig. 3 is a detail view showing the relationship of the bell crank member and the control extension member.

Fig. 4 is a detail view showing the signal control members associated with the cam unit extension members.

Fig. 5 is a detail view showing the signal control members in an operated position.

For illustrative purposes, this invention is shown as embodying a well known type of recording unit, which may be similar in construction to the Electromatic typewriter, shown and described in detail in U. S. Patent No. 1,777,055, and hence requires only the following brief description.

Referring to the drawings and particularly to Fig. 1, well known means are provided for actuating the type bars 16, comprising a constantly rotating roller 18, cooperating with a series of individual power units each comprising a cam 11, the engagement of the cams with the roller being controlled selectively by the character key bars 17.

Any suitable means may be provided to rotate the power roller, in the direction indicated by the arrow, which is adapted to cooperate with two rows of cam units arranged in the front and rear of the roller. The cam 11 may be provided to be pivoted on one arm of a bell crank lever 12 which is pivoted in the frame of the recording unit, as indicated generally by reference character 13, the other arm of the said bell crank lever is operatively connected with an arm of bell crank lever 14 by means of link 15. Another arm of the said lever 14 is connected to the type bars 16 in a well known manner, so as to effect operation of the type bars or any other suitable means connected to the bell crank levers upon selective operation of the controlling key bars 17.

The pivoted bell crank lever 12 is operated by the associated cam 11 whenever the latter engages the driven roller; the engagement of the cam with the roller is controlled by means of the

associated control key bar 17 in a manner which will now be briefly described.

Referring now to Fig. 2, the cams occupy normally the positions as shown in this figure, which 5 represents one of the rear bank of the units. In this position the impeller-arm 18 is urged, by the associated coil spring 19, against one of the impeller-lugs 20, which at the time is in the lower position, and tends to turn the cam 11 10 in a clockwise direction. This is prevented, however, by the engagement of one of the detents 21 on the cam, with the upper stop lug 22 on the stop lever 23. If, however, the corresponding key bar is operated, the bifurcated lower end (Fig. 15) of extension arm 24 associated with one of the said key bars 17 engages an arm 25 at the upper end of the stop lever 23 which is provided with an offset projection at its end which extends laterally through an opening in the 20 bell crank lever 12. The arm 25 of the stop lever 23 is then swung rearwardly or to the left as viewed in Fig. 1 about the pivot 26 and its lower end forwardly or to the right as viewed in this 25 figure, thus releasing the cam, which then turns under the influence of the spring urged impeller-arm 18. In doing so the upper serrated lobe of the cam is brought into engagement with the power roller, which turns in a counterclockwise direction and therefore causes a continued rolling movement of the cam until the high point 30 has been reached and passed. This causes the whole cam unit to swing around the pivot 13 so as to pull down the corresponding link and actuate one of the type bars or any other mechanism with which the cam unit may be connected.

After the high point of the cam is passed the cam loses contact with the roller, but the said impeller-arm 18 tends to continue the rotation 40 thereof by engaging the second impeller-lug 29 of cam 11 until the second detent 27 engages one of the stop lugs. Since the half rotation of the cam consumes only a small fraction of a second, it is difficult to release the key bar within this 45 short interval, so that it is the lower lug 28 which is first engaged, but upon the release of the key bar and the return of the stop lever 23 to normal position, this lug 28 disengages the detent, whereupon the impeller-arm rotates the cam slightly, 50 and the said detent then engages the upper stop lug 22.

It is obvious then that depression of a key bar releases the revolubly mounted cam to engage and be actuated by the power roller in turn operating the associated bell crank lever and its attached links to cause the associated mechanism such as the type bars and other operating mechanisms, to be operated. It is to be understood that an individual cam unit is provided for 55 each type bar or other functional mechanisms associated therewith.

The action of the cam mechanism has been described with respect to one of the rear bank of cam units; in the case of those of the forward 60 bank the operation is analogous, but the directions of movement, and the order of operation of the stop lugs, is reversed. For example, if the bifurcated arm 24-a is positioned to engage the arm 25-a at the upper end of stop lever 23-a 65 by virtue of operation of the associated key bar, the said arm is positioned rearwardly or to the left as viewed in Fig. 1, and the lower end of the stop lever 23-a is moved forwardly, that is, to the right as viewed in the said figure. This said 70 operation is effective to release the cam, by vir-

tue of positioning the lower stop lug 28-a out of the path of detent 21-a, thus permitting the spring-urged impeller arm 18-a to rotate the cam slightly in a clockwise direction to effect engagement of the lower lobe of cam 11 and power 5 roller. Upon completion of a half revolution of the cam 11, the second detent 27-a engages first the upper stop lug 22-a while the stop lever 23-a is in an operated position, but upon release of the associated key bar and the return of the 10 said stop lever to normal position, this lug 22-a disengages the said detent and the impeller-arm rotates the cam slightly so that the said detent then engages the lower stop lug 28-a, as shown in this figure. In this manner the bell crank 15 lever 12-a is rotated about the pivot 13-a to operate the associated type bar or any other mechanism associated therewith. For further structural details of the cam units, reference should be made to the above mentioned patent. 20

Referring now to Fig. 3, it is seen that the arms of the bell crank levers 12 are extended below the pivotal axis of the cams 11. This axis is indicated by the line B-B and is shown to lie in the same plane as the point of rotation or 25 axis of the power roller 10. The extension member is indicated by the reference character 30 for the rear cams and 30-a for the front cams. It is seen that the extension arm or member 30 is disposed along the major axis of the bell crank 30 lever 12, that is the major axis in the vertical plane which is indicated by the line A-A. This said member 30 is extended so as to protrude below the pivotal axis of the cam 11. The extension member is shown to be an integral part 35 of the bell crank lever in the associated figures; however, it is understood that it readily may comprise a separate member suitably secured to the bell crank members in the position as indicated in the drawings, and such variations and 40 modifications are encompassed in the scope of the present invention. At the lower end of the extension member 30, a cam roller 31 is rotatably mounted thereon, the pivot point or axis lying in the plane indicated by the line C-C. It is 45 noted that this axis line or plane is parallel to the axis line or plane B-B but is disposed beneath the last mentioned plane so as to be clear of the cams and power roller of the recording unit. 50

It has been mentioned hereinabove that the present invention is applicable to teleprinter transmitting systems and that the signal transmitting control members can be operated by the extension arms 30, and that such control members may be in the form of permutation bars or contacts. Referring now to Figs. 4 and 5, one form of signal control mechanism will be briefly described, since the permutation bar unit to be described forms no part of the invention per se, 55 the brief description to follow is deemed sufficient; for further structural details, reference may be made to the copending application Serial No. 113,798, filed Dec. 2, 1936, now Patent No. 2,161,564, June 6, 1939. In the said copending 60 application the permutation bar unit is claimed only; however, the present invention is shown therein but not claimed in the application referred to, so that the present application represents a divisional application of the copending 65 case.

The signal transmitting unit comprises a plurality of rotatable bars 35, all disposed in the same horizontal plane and parallel to the axis line or 70 plane indicated by the line C-C in Fig. 3. The 75

bars are suitably mounted in end plates secured to the frame of the machine which also are adapted to support the rods 43 which act as guide and supporting rods for the selector members 37.

5 The said selectors 37 are slidably mounted on the said rods and are adapted to be engaged by the cam rollers 31 to be positioned thereby. Each selector 37 has a plurality of equally spaced studs 38 fixed thereon, three studs on each side of the 10 selector member and alternately positioned thereon.

The said studs are adapted to engage certain of the keys 36, which are suitably secured to the permutation bars 35, when the selectors 37 are 15 displaced by the extension members 30 and cam rollers 31. The keys 36 are arranged to extend above and below the bars 35 as shown in the said figures. The purpose of this arrangement is explained in detail in the said application referred 20 to hereinabove and need not be repeated here. It is sufficient to point out that the keys protruding above the bars 35 are engaged by the studs 38 disposed on the selectors 37 which are displaced or operated by the rear cam units, and the keys 25 extending below the said bars are engaged by the studs on the selectors displaced by the front cam units.

The keys 36 are secured to the associated bars 35 so that the displaced selectors are adapted to 30 displace or partially rotate the said bars when the studs on the selectors engage the corresponding keys. According to the number of keys engaged by the selector studs, various and different combinations of bars 35 are rotated or displaced 35 upon operation of the selectors 37. Fig. 5 shows one of the selector members displaced by the extension members and cam roller associated with one of the front cam units and shows that the keys secured to permutation bars numbers 2 to 5 40 are engaged by the selector studs to partially rotate the said bars. Suitable control or switch arms 56 are suitably disposed so as to be released by keys 60 and displaced by the associated springs from their normal position. A group of three 45 switch arms are disposed at each end of the machine, this fact, however, is not of importance and merely a matter of choice. It is seen that the switch arms 56 associated with the permutation bars 53 numbers 2 to 5 are positioned to 50 engage the contacts 62 instead of the normally engaged contacts 58. The contacts correspond to the printer controlled contacts in the known Baudot or combinational code systems and can obviously be included in said printing telegraph 55 systems for control purposes in a manner well known to those skilled in the art. The description of one form of control member controlled by the extension members 30 related to controlling indirectly the signal control contacts by means 60 of permutation bar units, however, it is obvious that groups of contacts can be so disposed as to

be engaged directly by the cam rollers 31 when displaced by the controlling bell crank levers and cams. This is a matter of choice and obviously falls within the scope of the present invention.

5 While there has been shown and described and pointed out the fundamental novel features of the invention as applied to a single modification, it will be understood that various omissions and substitutions and changes in the form and details 10 of the device illustrated and in its operation may be made by those skilled in the art without departing from the spirit of the invention. It is the intention therefore to be limited only as indicated by the scope of the following claims.

15 What is claimed is as follows:

1. A device of the character described comprising a plurality of operable key bars, individual power operated units and means for selectively controlling and operating the said units upon 20 operation of the key bars, said units comprising a revolvable cam and supporting member therefor, an extension member disposed longitudinally of the cam supporting member and forming a part thereof, and control means adapted to be engaged 25 by the said extension member upon operation of the said power operated units.

2. A device of the character described comprising a plurality of operable key bars, a power driven roller, individual units comprising a 30 revolvable cam and supporting member therefor and means for selectively controlling the units upon operation of the key bars so that the cam and roller are engaged to actuate the cam and supporting member, a control member, and an 35 extension member disposed on the said supporting member and extending below the common plane in which the axes of said cam and roller are disposed to engage the control member upon operation of the cam and supporting member.

40 3. A device of the character described comprising a plurality of operable key bars, individual power operated units and means for selectively controlling and operating the units upon operation of the key bars, said units comprising a member having extensions to support a revolvable cam element and a control element in two different planes, means whereby the cam element is supported in one plane and the control element in 45 another plane, this last mentioned plane being located below the first said plane, and a plurality of slidable members disposed in a horizontal plane below the cam elements, each said member having means disposed in the path of the related control elements so that upon operation of the related cam element the corresponding slidable member is displaced.
